(57) **CLAIM**

I claim the ornamental design for a combined shade cover with tie retainer, as shown and described.

DESCRIPTION

FIG. 1 is a perspective view of a combined shade cover with tie retainer, showing my new design in an environment of use;

FIG. 2 is an end view of thereof;

FIG. 3 is a side view thereof;

FIG. 4 is a front view thereof;

FIG. 5 is an opposite side view thereof;

FIG. 6 is a back view thereof; and,

FIG. 7 is an opposite end view thereof.

The dot-dot-dash line shown on the shade cover in FIG. 1 represents stitching that forms part of the claimed design. The evenly spaced broken lines shown on the shade cover and tie retainer in FIGS. 1, 4, and 6 represents stitching that forms part of the claimed design. All other broken lines shown in FIG. 1-7 represent environment that forms no part of the claimed design.
